UNITED STATES PATENT OFFICE.

GRANT F. DISCHER, OF MILWAUKEE, WISCONSIN, ASSIGNOR TO LOUIS SCHLESINGER AND HENRY HELLWEG, BOTH OF MILWAUKEE, WISCONSIN.

PACKAGE HOLDER.

1,411,004.

Specification of Letters Patent. Patented Mar. 28, 1922.

Application filed December 12, 1919. Serial No. 344,409.

To all whom it may concern:

Be it known that I, GRANT F. DISCHER, a citizen of the United States, residing at Milwaukee, in the county of Milwaukee and State of Wisconsin, have invented certain new and useful Improvements in Package Holders, of which the following is a specification, reference being had to the accompanying drawing, forming a part thereof.

10 This invention relates to package holders and the object of the invention is to improve package holders in the manner to be hereinafter described and claimed.

Referring to the drawings, which accompany this specification and form a part hereof, which drawings illustrate an embodiment of this invention and on which drawings the same reference characters are used to designate the same parts wherever 20 they may appear in each of the several views, Fig. 1 is an elevation of the package holder secured to a support, parts being shown in section; Fig. 2 is a plan view of the package holder and part of the support shown by 25 Fig. 1, Fig. 3 is a cross-section of the package holder and support, the section being taken on the line 3—3 on Fig. 1 looking in the direction indicated by the arrows; and Fig. 4 is a longitudinal section of part of the 30 package holder and support, the section being taken on the line 4—4 on Fig. 3 looking in the direction indicated by the arrows.

Referring to the drawings, the reference numeral 1 designates a support of any suitable character and which is conventionally illustrated as the running board of an automobile. A package support member 2 can be engaged with a clamp member 3 in different positions of extension, or retraction, 40 with respect to the support 1.

The package supporting member 2 is provided with apertures separated by cross-bars 4 and a strap, or any other suitable fastening means, not shown, can be fastened 45 to the package supporting member 2 by being engaged with one or more of the cross-bars 4 in a manner which will be readily understood. The package supporting member 2 is also provided with alternating depressions 5 and elevations 6 which are 50 adapted to register with and co-act with elevations 7 and depressions 8 on the clamp 3. The clamp 3 overrides the package supporting member 2 and is provided with any suit-

able securing means as, for example, the 55 screw 9 and the locknut 10.

In the specific construction illustrated by the drawings, the package supporting member 2 is shown as provided with a flush upper surface from which depend the sides 11 and 12 and the flanges 13 and 14 are shown as extending outwardly from the bottoms of the sides 11 and 12. The depressions 5 and elevations 6 are shown as formed on the tops of the flanges 13 and 14 and the clamp 3 is 60 shown as provided with flanges 15 and 16 which overlie, respectively, the flanges 13 and 14 and are provided on their undersides with the elevations 7 and depressions 8. The 65 top of the clamp 3 does not project above the top of the package supporting member 2 whereby a package such as a trunk or box, for example, can rest securely upon the flat upper surface of the package supporting member 2.

The clamp 3 is provided with a sufficient clearance 17, so that the depressions 5 and elevations 6 can be disengaged from the co-acting elevations 7 and depressions 8 on the clamp 3 to change the position of the package supporting member 2 with respect to the clamp 3 and the support 1.

The operation of the device is as follows: The package supporting member 2 is adjusted with respect to the clamp 3 to the 85 desired position and the screw 9 is tightened and then the lock-nut 10 is tightened. Depressions 5 and elevations 6 on the package supporting member 2 match with and engage with elevations 7 and depressions 8 on the clamp 3, so that the package supporting member 2 is firmly held in its correct longitudinal position. The flanges 15 and 16 on the clamp 3 extend a sufficient distance 90 longitudinally of the package supporting member 2 to insure against a twisting or rotational movement of the package supporting member 2.

What is claimed is:

1. In a package holder, the combination 100 with a package supporting member having an unobstructed upper surface which is provided with apertures, the package supporting member having depending sides with flanges at the bottoms of the sides, of a clamp 105 provided with flanges which are adapted to overlie the flanges on the package supporting member, and means for securing the

clamp and package supporting members together and to a support.

2. In a package holder, the combination with a package supporting member having an unobstructed upper surface which is provided with apertures, the package supporting member having depending sides with flanges at the bottoms of the sides, of a clamp provided with flanges which are adapted to
- 5
- 10
- 15
- 16

overlie the flanges on the package supporting member, the flanges on the clamp and on the package supporting member being pro-

vided with elevations and depressions adapted to coact to prevent relative displacement of the package supporting member with respect to the clamp, and means for securing the clamp to a support with the package supporting member held between the clamp and a support with the elevations on the flanges received within depressions on the other flanges.

In witness whereof I hereto affix my signature.

GRANT F. DISCHER.
